US0D1032191S

(12) United States Design Patent (10) Patent No.: US D1,032,191 S
(45) Date of Patent: * Jun. 25, 2024

(54) WEAPON CASE

(71) Applicant: NEGRINI S.R.L., Quistello (IT)

(72) Inventor: Graziano Negrini, Quistello (IT)

(73) Assignee: NEGRINI S.R.L., Quistello (IT)

() Term: 15 Years

(21) Appl. No.: 29/833,672

(22) Filed: Apr. 6, 2022

(30) Foreign Application Priority Data

Oct. 6, 2021 (EM) 008716203-0001

(51) LOC (14) Cl. 03-01

(52) U.S. Cl.

USPC D3/220; D3/262
